DESIGN FOR A WOMAN'S SPORTS GARMENT

Katharine H. Deeble, St. Louis, Mo.

Application October 9, 1937, Serial No. 72,096

Term of patent 7 years

To all whom it may concern:

Be it known that I, Katharine H. Deeble, a citizen of the United States and resident of St. Louis, in the county of St. Louis and State of Missouri, have invented a new, original, and ornamental Design for a Woman's Sports Garment, of which the characteristic feature is the particular collar and belt in combination with the yoke and sleeves, as shown, and of which the following is the specification, reference being had to the accompanying drawing forming part thereof.

Fig. 1 is a front view of the garment embodying the invention; and

Fig. 2 is a rear view of the garment.

I claim:

The ornamental design for a woman's sports garment, as shown and described.

KATHARINE H. DEEBLE.
